UNITED STATES PATENT OFFICE

LEO J. LAMBERT, OF SALEM, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY

FOLDING MACHINE AND METHOD

Application filed April 9, 1924. Serial No. 705,223.

The present invention relates to methods of and machines for folding flexible material, and more particularly to methods of and machines for folding the margins of shoe uppers, such as vamps, quarters, tongues and the like.

Folding machines of the above-described character, of the type that operate successively upon successive portions of the stock, 10 are generally provided with a folder or plow for initiating a fold in successive portions of the margin of the shoe upper, and with a fold presser that presses down the successive folds thus initiated into contact with the body of 15 the upper. It is desirable that the contacting parts of the margin and of the body of the upper be symmetrically disposed to the line of fold. In practice, however, whether the folding be done by machines of the above-described 20 character, or by hand, such symmetrical folding is not attainable. During each folding action of the plow, the yet unfolded portions of the margin exert a pulling force upon the portion that is in the act of being 25 folded; and this pulling force causes the fold to be pressed down upon a portion of the body of the upper that is a little to one side of its symmetrically disposed portion.

The consequence of this unsymmetrical 30 folding is that the folded upper will not lie flat, but is more or less twisted. If the upper is of substantial width, as in the case of vamps and quarters, and as the twisting effect is confined almost entirely to the folded marginal portion, the twist is not very noticeable. 35 The twist thus produced in very narrow uppers, however, like tongues, straps, and the like, may be very great.

It is accordingly an object of the present 40 invention to control the above-described twist. With this end in view, a feature of the invention resides in pulling upon each marginal portion during the act of folding in a direction opposed to the pull exerted by the unfolded portion of the margin. The pull so 45 exerted upon each marginal portion may, however, within the scope of the invention, be controlled not only to balance the natural pull exerted by the unfolded portion of the margin, but to assume any other desired value

and may, in fact, assume a value such as to increase the natural pull exerted by the said unfolded portion.

A further object is to provide a novel mechanism for effecting the said controlled pulling 55 action.

A further object is to provide an improved mechanism for facilitating the turning of portions of the material having curved margins. 60

Another object is to provide an improved cutting mechanism for snipping the margin, at the will of the operator, prior to the folding operation.

Other and further objects will be explained 65 in the following description, and will be particularly pointed out in the appended claims, it being understood that the invention consists of the folding method and machine a preferred embodiment of which is illustrated 70 and described herein, and that it is intended to express in the appended claims all the novelty that the invention may possess.

In the accompanying drawings, Fig. 1 is a view in side elevation, partly in longitudinal section, of a machine constructed according to a preferred embodiment of the present invention; Fig. 2 is an elevation of the forward part of the machine, viewed from the side opposite to that of Fig. 1; Fig. 3 is a section 75 of the forward part of the machine, taken upon the line 3—3 of Fig. 2, looking in the direction of the arrows; Fig. 4 is a vertical section taken upon the line 4—4 of Fig. 3, looking in the direction of the arrows; Fig. 5 is an enlarged view of a portion of the mechanism shown in Fig. 4; Fig. 6 is a view similar to Fig. 5, showing the parts in different positions; Fig. 7 is a fragmentary elevation of Fig. 5, looking from the right; Fig. 8 is a similar view, looking from the rear of Fig. 5; 80 Figs. 9 and 10 are sections taken upon the lines 9—9 and 10—10 of Figs. 5 and 6, respectively, looking in the directions of the arrows; Fig. 11 is a detail plan, illustrating the 85 operation upon convex corners of the upper; Fig. 12 is a section taken upon the line 12—12 of Fig. 11, looking in the direction of the arrows; Fig. 13 is a further enlarged, perspective view, partly broken away, of the 90 95 100

parts illustrated more particularly in Figs. 7 and 8; Figs. 14 and 15 are views of folded uppers; Figs. 16, 17 and 18 illustrate the folding of the uppers shown in Figs. 14, 15 and 19, 5 respectively; Fig. 19 illustrates an upper folded as illustrated in Fig. 18; Fig. 20 is an enlarged diagrammatic view illustrating the preferred retainer and the folder of the present invention; Fig. 21 is a section taken upon 10 the line 21—21 of Fig. 20, looking in the direction of the arrows; Fig. 22 is a view of an upper prior to folding; Fig. 23 is a further enlarged, perspective view, with portions broken away, illustrating the parts operating 15 upon a concave curve of the upper; Fig. 24 is a view corresponding to Figs. 16, 17 and 18, showing the relative positions of the operating parts of the machine; Fig. 25 is a perspective view, with parts broken away, on the 20 same enlarged scale, illustrating more particularly the knife action; and Fig. 26 is a perspective view of parts of the machine shown detached for clearness.

A shoe upper is shown unfolded in Fig. 22. 25 The margin 2 is intended to be folded upon the body 4 of the upper about a line of fold 6. The line along which the edge of the margin 2 will lie after the margin has been folded is indicated at 8 (shown dotted in Fig. 30 22 and full in other figures). The margin 2 and the portion of the body of the upper bounded between the lines 6 and 8 have successive portions that are symmetrically disposed with respect to the line of fold 6. The 35 term "symmetry" will be used in the specification and the claims in its ordinary sense. Thus, the first two such symmetrically disposed portions are indicated at 10 and 12, disposed on opposite sides of the line 6 along a 40 normal to this line; the next succeeding two are indicated at 14 and 16, similarly disposed; the next succeeding two, similarly, at 18 and 20; the next succeeding two at 22 and 23; and so on throughout the margin of the upper, 45 and along the curved, as well as the straight, portions of the margin.

The portion 10 of the margin of the shoe upper should obviously be folded into contact with its symmetrically disposed portion 12 50 of the body portion of the upper; the portion 14 into contact with its symmetrically disposed portion 16; and so on. In practice, however, the portion 10 is overlapped into contact with the portion 16; the portion 14 into contact with the portion 20; and so on, as is illustrated in Fig. 19. The showing in Fig. 19 is somewhat exaggerated, in order to illustrate more clearly the principle involved. The reason why this overlapping 55 folding occurs will be readily understood when it is reflected that, during the folding of the portion 10 toward the portion 12, the yet unfolded portions 14, 18, 22, and so on, of the margin 2 pull upon the portion 10 to dis- 60 place it towards the portion 16; during the

70 folding of the portion 14 toward the portion 16, the yet unfolded portions 18, 22, and so on, of the margin 2 pull upon the portion 14 to displace it towards the portion 20; and so on. When the margin 2 is finally folded, the resulting strains set up in the folded margin 75 will cause the upper to twist, as is illustrated in Fig. 18. An additional objection lies in the creases 25 that are produced in the body of the upper in the neighborhood of the lines 6 and 8, more or less parallel to the direction 80 of displacement of the margin 2, as is illustrated in Fig. 19.

A chief object of the present invention is to fold the portion 10 accurately into contact with the portion 12; the portion 14 accurately into contact with the portion 16, and so on, as is illustrated in Fig. 15. No strains or creases will be introduced into the upper by this method of folding, so that the finally 85 folded upper will lie absolutely flat, as is illustrated in Fig. 17.

According to the preferred method of attaining this result, the portion 10 is pulled away from the portion 16, or away from the 90 adjacent and yet unfolded margin 2, in the direction of the arrow, Fig. 22, during the folding action, to counterbalance the pull exerted by the portions 14, 18, 22, and so on, of the yet unfolded margin 2. The portion 10 is thus folded flat into contact with the portion 12. A similar pull in the direction of the arrow, when folding the portion 14, will result in the portion 14 being folded flat into 95 contact with the portion 16; and so on.

The preferred mechanism for effecting this 100 result comprises a folder or plow 32 that moves at first parallel to the plane of the upper, along the dotted line 26, Figs. 20 and 21, and then obliquely toward the plane of the upper, along the dotted line 28. Toward the 105 end of its travel along the line 26, the folder engages a portion of the margin of the upper, as is illustrated in Figs. 5 and 9. The line 26 is oblique to the line 6, substantially along 110 the line 4—4 of Fig. 3. This oblique movement of the folder along the line 26, therefore, results in a pulling action, upon the portion of the margin 2 which it engages, in 115 the direction of the arrow, Fig. 22. The folder thus not only folds the margin, but pulls it, as well. The pulling effect is increased during the oblique movement of the folder along the line 28. This combined folding and 120 pulling action would not, however, by itself, suffice, for the margin would have a tendency to slip past the folder, instead of being pulled along by it. This tendency is particularly to 125 be guarded against because the folder folds the margin through an angle as great as one hundred and eighty degrees. To prevent this happening, therefore, the folder is caused to engage the margin against a downwardly inclined face 246 (Fig. 21) of a member 130 135 140 145 150 155 160 165 170 175 180 185 190 195 200 26. The member 153 may conveniently be the retainer. During the subsequent movement of the folder along the line 28, the folder positively drags the folded margin frictionally past the retainer 153, preventing any slipping, and safely laying the portion of the margin which it engages flat into contact with the symmetrically disposed portion of the body of the upper.

10 This accomplished, the folder or plow 32 is retracted. A lower feed block 41 (Fig. 2) and an upper feed point 30, shown more particularly in Figs. 2, 3 and 24, thereupon grip the upper between them, and advance the 15 folded portion over a platform or support 24, to a fold presser 42. The fold presser 42 presses the folded portion of the margin flat against the body portion. The feed point and the feed block release their hold on the upper 20 just before the fold presser has commenced to act, and just after the retainer has gripped the upper. They thereupon retrace their movement, during the fold pressing action, the retainer 153 helping to hold the stock stationary. The cycle of operation is then 25 repeated. The margin thus becomes folded step by step.

It will be obvious that the novel folder of the present invention may be embodied in 30 many different types of folding machines. It is therefore unnecessary to distract the attention from the features of novelty of the present invention by describing in detail any particular type of feed mechanism, fold presser 35 or retainer. A full description of the feed mechanism, fold presser and retainer of the illustrative machine may be found in patents to Andrew R. Ridderstrom, Nos. 1,527,395 and 1,527,396, granted February 24, 1925. It 40 will, however, be necessary to describe the folder-actuating mechanism of the present invention; and as the folder is preferably operated in synchronism with the fold presser, and from the same operating mechanism, it will be desirable to describe very briefly the 45 illustrative fold presser and its operating mechanism.

The fold presser 42 is floatingly pivoted at 146, Fig. 1, to one end of a link 148 the other 50 end of which is eccentrically connected by a pin 150, with a spiral gear 152. The spiral gear 152 meshes with a spiral gear 154 upon a driving shaft 66. The exterior surface of 55 the fold presser is cylindrical, as shown at 156, so as to rock within a cylindrical bearing 158 provided at the free end of an arm 160 the other end of which is pivoted at 162. The fold presser is spring-pressed towards 60 the support 24 by a compression spring 166 that is mounted upon a rod 168 extending through an opening 143 in the arm 160 and screw-threaded into the frame, as shown at 65 145. By means of the screw threads, the pressure of the spring upon the arm 160 may be adjusted, the ends of the spring being con-

fined between the arm and a knurled head 170 upon the rod 168. By means of this construction, the fold presser is pivotally actuated in a plane at right angles to the plane of feed, with a yielding action of the fold presser upon the fold, relieving the strain thereon, while permitting a positive separation of the fold presser from the upper by the link 148.

The folder is driven from the same gear 152 that drives the fold presser, through a link 161 that is pivoted, at one end 63, to the link 148 and, at the other end 65, to an arm 67. The arm 67 is rigidly connected to a shaft 69. Movement of the link 161, therefore, results in rocking the shaft 69. A gear 71 that is rigidly mounted upon the shaft 69 meshes with a rack 73 that is carried on the under side of a horizontally disposed support 75. The support 75 and the rack 73 carried thereby are obliquely disposed to the line of feed. Rocking of the gear 71 is therefore converted into a reciprocating movement of the support 75 in a horizontal plane and oblique to the line of feed. The folder 32 is mounted upon the support 75 so as to move therewith. This construction, therefore, causes the folder to reciprocate horizontally along the line 26 oblique to the line of feed.

It remains to describe the construction that renders possible the movement of the folder along the line 28. A sub-support 77 is pivoted to the support 75 about a pivot 79. The folder is pivoted to the sub-support 77 about a pivot 81 that is perpendicular to the pivot 79. When the folder reaches the end of its path 26, its tail 83 engages an abutment 85. Further travel of the support 75, therefore, causes the abutment to act against the tail 83, effecting the pivotal movement of the folder 105 about the pivot 81. As the support 75 continues its oblique travel, the folder is caused to ride over the downwardly inclined face 246 (Fig. 21) of the retainer 153, the retainer being situated in the oblique line of travel 110 of the folder for this purpose, and being shaped to effect this result. This engagement of the folder with the retainer is permitted by the sub-support 77 pivoting about the pivot 79 in a direction at right angles to the direction of pivotal movement of the folder about the pivot 81.

Upon the return movement of the support 75, a spring 87 effects the return of the sub-support 77 to its normal position, and a spring 89 performs a similar function for the folder 32. The spring 87 is shown as a plurality of leaf springs fastened at one end between fixed abutments 91 and engaging at the other end an abutment 93 that is integral with the sub-support 77. The spring 89 is also constituted of a plurality of leaf springs and is fastened at one end 95 to a support 365 and its other end engages a hook 120 125

97 that is integral with the folder 32. The end 95 may be fastened by riveting, or in any other desired manner.

The abutment 85 is rendered yielding to permit the folder to yield when occasion requires. To this end, it is slidably mounted in an obliquely disposed groove 99 in the forward portion of the frame of the machine, parallel to a groove 101 in which the support 75 is slidably mounted (see Fig. 3). A block 103 is fastened to a projecting horn 106 of the frame by pins 105, and acts as a common guide between the slidably mounted members 75 and 85. A coil spring 107 is interposed between the block 103 and the abutment 85 to hold the abutment normally in the extended position indicated in the drawings. The spring 107 is stronger than the springs 87 and 89, so that it will not be compressed until after a force more unyielding than the springs 87 and 89 is opposed to the spring 107. An adjustable stop 109 at the other end of the abutment adjustably engages the block 103 to adjustably limit the normal position of the abutment. This stop adjustably determines the time of engagement of the tail 83 by the abutment 85, and therefore controls the degree of movement of the folder 32 about its pivots 81 and 79. This movement, in turn, determines the degree of pull of the folder against the margin of the upper. Depending upon the adjustment of the stop 109, therefore, the pull of the folder against the margin may exactly balance the natural pull of the unfolded margin, to produce a fold as in Figs. 15 and 17, or it may assume any desired value less than or greater than such value. The pull may, in fact, be so great, as to overbalance the above-mentioned natural pull, to produce a fold as illustrated in Fig. 14, with a corresponding twist as shown in Fig. 16, opposite to the natural twist, illustrated in Fig. 18. Creases 27 may thus be produced in a direction opposite to the creases 25 of Fig. 19.

Summarizing the operation of the preferred machine, as thus far described, the shoe upper is advanced over the support 24, step by step, by the feed point 30 and the feed block 41; the retainer 153 helps to hold the stock stationary during pauses in the feed; the folder 32 is actuated, first in a plane parallel to the line of feed along a line oblique to the line of feed, and later obliquely to the plane of the material, against the retainer, during pauses in the feed, to initiate a fold in successive portions of the margin, step by step; and the fold presser 42 is actuated step by step, during pauses in the feed, to press flat the folds successively initiated by the fold presser during immediately prior pauses in the feed. Each folded portion is pressed while the next succeeding portion is being folded. The fold presser and the folder are actuated in synchronism from

a common actuating mechanism. A gage 436 (Fig. 2), secured by a screw at 438, is provided just rearward of the knives 352 and 353, hereinafter described, and engages the edge of the stock as it is bent up by the stationary knife 353 to gage the material.

The invention comprises also a novel cutting mechanism for snipping the margin of the stock prior to the folding operation. The snipping is performed, according to the preferred embodiment of the present invention, by a movable knife 352 (Fig. 23), cooperating with a stationary knife 353. The movable knife is pivoted at 59 to the upper end of a bracket 61 and is normally maintained in ineffective position by a spring 354. The knife is provided with a tail 356 that extends downward, as shown. By means of the tail 356, the knife may be caused to be actuated, at the will of the operator. A screw 62 is mounted in an elongated slot of the bracket 61 to provide for adjusting the knives.

According to the preferred construction, a member 362 is adapted to be interposed between the tail 356 and a plug 363 upon the rear end of the slide 75. The plug 363 may be provided upon a plate 365 that may be fastened to the sub-support 77 by a fastening member 367. So long as this member 362 is so interposed, the plug 363 will strike it at the end of each return movement of the support. The force will be communicated by the member 362 to the tail 356, which will therefore cause the knife to be actuated about its pivotal point, in opposition to the force of the spring 354 (Fig. 2). At each forward movement of the support, the spring 354 will return the knife to ineffective position. The knife will therefore cut once to each cycle of operation of the folder. To adjust the cutting action, the member 362 is caused to engage the tail 356 not directly, but through an adjustable screw 364.

The member 362 is pivotally mounted at 366 to the top of a vertically slidable rod 368. The pivotal mounting of the member 362 permits it to move back and forth under the influence of the plug 363 and the spring 354, respectively. All that is necessary to render the knife effective, therefore, is to slide the member 362 at the top of the rod 368 vertically into the path of reciprocation of the support 75. In order that such vertical movement may be effected in any position of the support 75, the upper end of the member 362 is made wedge-shaped, as shown.

The vertical movement of the rod 368 may be effected by engaging its lower end by an arm 370. Movement of the arm 370 in one direction will cause the rod 368 to be raised. Movement of the arm 370 in the opposite direction will permit the rod to fall by gravity out of the way of the reciprocating plug 363. The arm 370 is secured to one end of a rock

shaft 151 that extends transversely across the machine, as indicated more particularly in Fig. 3, to the other end of which is secured a lever 176. The lever 176 is connected by a link 178, Figs. 1 and 3, to a lever 179 that is secured to a rock shaft 188. The rock shaft 188 is provided with a fixed arm 183 that is connected with a treadle rod 187. By actuating the treadle rod, the rock shaft 188 will be rocked, and the rocking movement of the rock shaft will be communicated, through the link 178 and the lever 176, to the rock shaft 151, thereby rocking the arm 370.

The rock shaft 188 is shown provided in Fig. 1 with a second arm and a second treadle rod that, together with the arm 183 and the treadle rod 187, are intended to control the rate of feed of the feed members 30 and 41, as is more fully described in a copending application by the said Ridderstrom, Serial No. 652,169, filed July 17, 1923. The feed and the knife cuts are thus controlled together. Further description is omitted here, because forming no part of the present invention.

The mechanism for operating the feed members is not described herein, because unnecessary to an understanding of the present invention, as above stated. The feed members themselves, however, are slightly changed from the constructions explained in the above-mentioned patents. This change consists in moving the feed point 30 farther to the left, as indicated by the bend 369 in Fig. 24, so as to cause it to reciprocate in a path between the fold presser 42 and the retainer 153. The feed block is correspondingly changed in position. The limits of reciprocation are indicated in this figure in dotted lines. The paths of movement of the feed elements and of the folder thus converge towards the fold presser. This construction enables the operator to turn corners more readily, as illustrated in Fig. 11, since it brings the feed members closer to the point of operation of the plow. The relative positions of the feed point and the plow, in fact, approximate those disclosed in the said application Serial No. 652,169. The turning is effected about the feed point and the feed block as a pivot, just before the feed point rises to retrace its feeding movement, and before either the retainer or the fold presser has gripped the stock. This is very important for it is possible, by means of the above-described treadles, to vary the length of the feed strokes from a maximum to zero. The knives are situated opposite to the retainer, as is also illustrated in Fig. 24.

The oblique movement of the folder brings it so close to the fold presser as to make it necessary to position the latter farther away in the direction of feed than in the said application, Serial No. 652,169. This positioning of the fold presser, however, brings it out of the range of action of curved portions

of the stock. To compensate for this, the fold presser is provided with two projections 371 and 373 that are separated by an intermediate portion 375. The intermediate portion 375 permits the folder to advance towards the fold presser as close as may be desired; and as it is designed to act on the straighter portions of the work, its greater distance from the operating instrumentalities does not affect the operation of the machine. Provision is thus made also for permitting the folder to yield more about its pivots when encountering unusually thick places in the stock, as at seams. Concave portions of the work are pressed by the projection 373, which is situated rearward of the separating portion 375, as is illustrated in Fig. 28. The similarly situated projection 371 acts on convex portions of the work, as is illustrated in Fig. 11.

Many details of the illustrative machine have not been illustrated herein, and many illustrated parts have not been described, because unnecessary to an understanding of the present invention, and because full particulars may be obtained in the aforesaid patents and application. The elements of novelty, furthermore, though fully explained, are by no means restricted to the exact embodiments thereof that are illustrated and described herein. Modifications and changes will readily occur to persons skilled in the art, and all such are considered to fall within the scope of the invention, as defined in the appended claims.

What is claimed is:

1. A method of folding sheet material about a line of fold comprising relatively feeding the material, and progressively folding successive portions on one side of the line into contact with variably selected predetermined successive portions on the other side of the line.

2. A method of folding sheet material about a line of fold that constitutes a line of symmetry for corresponding successive portions of the material on each side of the line, whereby each two corresponding symmetrically disposed portions are disposed on opposite sides of the line along a normal to the line, the said method comprising progressively operating separately upon each of the said successive portions on one side of the line to fold them each into contact with the corresponding symmetrically disposed portion on the other side of the line.

3. A method of folding sheet material about a line of fold that comprises successively folding successive portions of the material on one side of the line part way toward the material on the other side of the line, moving each partly folded portion so produced towards the next previously folded portion in a direction at an angle to the direction of folding, and folding each of the said

partly folded and moved portions the rest of the way into contact with the material on the other side of the line.

4. A method of folding sheet material about a line of fold that constitutes a line of symmetry for corresponding successive portions of the material on each side of the line, whereby each two corresponding symmetrically disposed portions are disposed on opposite sides of the line along a normal to the line, the said method comprising successively folding successive portions on one side of the line about the line part way toward the material on the other side of the line, moving each partly folded portion so produced towards the next previously folded portion in a direction at an angle to the direction of folding, folding each of the said partly folded and moved portions the rest of the way into contact with the corresponding symmetrically disposed portion on the other side of the line, and pressing the contacting portions together.

5. A method of folding sheet material about a line of fold that comprises feeding the material, folding the material on one side of the line towards the material on the other side of the line, and moving the said material on the said one side of the line in the direction of feed relatively to the said material on the said other side of the line during the folding action.

6. A method of folding sheet material about a line of fold that comprises folding the material on one side of the line into engagement with a member, and frictionally dragging the folded material past the member into contact with the material on the other side of the line.

40 7. A method of folding sheet material about a line of fold that comprises gripping the material on one side of the line with a member and advancing the member to feed the material, gripping with a second member the material on the said one side of the line rearward of the gripping member at the end of the feeding movement, folding the material on the other side of the line into engagement with the second-named member, frictionally dragging the folded material past the second-named member into contact with the material on the said one side of the line, and turning the material about the first-named member as a pivot.

55 8. A machine for folding sheet material about a line of fold that constitutes a line of symmetry for corresponding successive portions of the material on each side of the line, whereby each two corresponding symmetrically disposed portions are disposed on opposite sides of the line along a normal to the line, the said machine having, in combination, means for folding portions on one side of the line into contact with portions on the other side of the line, and means for insuring

that each portion on the said one side of the line shall be folded into contact with the corresponding symmetrically disposed portion on the other side of the line.

9. A machine for folding sheet material about a line of fold that constitutes a line of symmetry for corresponding successive portions of the material on each side of the line, whereby each two corresponding symmetrically disposed portions are disposed on opposite sides of the line along a normal to the line, the said machine having, in combination, means for folding portions on one side of the line into contact with portions on the other side of the line, and means for insuring that each portion on the said one side of the line shall be folded into contact with a portion on the other side of the line that is symmetrically disposed to the portion on the said one side of the line that was next previously folded.

10. A machine for folding sheet material about a line of fold that comprises means for successively folding successive portions of the material on one side of the line towards the material on the other side of the line and for moving each of the said portions towards the next previously folded portion during the folding action in a direction at an angle to the direction of folding, and means for pressing the folded portions.

11. A machine for folding sheet material about a line of fold that constitutes a line of symmetry for corresponding successive portions of the material on each side of the line, whereby each two corresponding symmetrically disposed portions are disposed on opposite sides of the line along a normal to the line, the said machine having, in combination, means for successively folding successive portions on one side of the line towards the material on the other side of the line and moving each of the said portions towards the next previously folded portion during the folding action to cause corresponding symmetrically disposed portions on each side of the line to contact, and means for pressing the contacting parts together.

12. A machine for folding sheet material about a line of fold having, in combination, means for feeding the material, and means for folding the material on one side of the line towards the material on the other side of the line and for moving the said material on the said one side of the line in the direction of feed relatively to the said material on the other side of the line during the folding action.

13. A machine for folding a sheet of material about a line of fold having, in combination, a folder, and means for actuating the folder substantially parallel to the plane of the sheet to cause the folder to engage a portion of the material on one side of the line and for thereupon actuating the folder towards a portion of the material on the

- other side of the line to fold the engaged portion of the material into contact with the material on the said other side of the line.
14. A machine for folding a sheet of material about a line of fold having, in combination, a folder, and means for actuating the folder to engage successive portions of the material on one side of the line to initiate folds in the material, and for thereupon actuating the folder at an incline towards previously folded portions and towards portions of the material on the other side of the line to fold the engaged portions of the material into contact with the material on the said other side of the line.
15. A folding machine having, in combination, a folder for folding a sheet of material about a substantially straight line of fold, and means for actuating the folder along a path oblique to the line into engagement with the material on one side of the line to fold the engaged material about the line of fold toward the material on the other side of the line.
16. A folding machine having, in combination, a folder for folding a sheet of material about a substantially straight line of fold, and means for actuating the folder along a path oblique to the line and lying wholly on one side of the sheet into engagement with the material on one side of the line to fold the engaged material about the line of fold toward the material on the other side of the line.
17. A folding machine having, in combination, a folder for folding a sheet of material about a substantially straight line of fold, and means for actuating the folder along a path parallel to the sheet and oblique to the line into engagement with the material on one side of the line to fold the engaged material about the line of fold toward the material on the other side of the line.
18. A folding machine having, in combination, a folder for folding a sheet of material about a line of fold, a member, and means for relatively actuating the member and the folder past each other along a path oblique to the line, the folder and the member being constructed and arranged to engage the material frictionally between them during their relative actuation past each other to cause the material to be dragged frictionally past the member.
19. A folding machine having, in combination, a folder for folding a sheet of material about a line of fold, a member, and means for actuating the folder to engage a portion of the material on one side of the line and to fold the material into engagement with the member and past the member into contact with a portion of the material on the other side of the line to cause the engaged portion of the material to be dragged frictionally past the member.
20. A machine for folding a sheet of material about a line of fold having, in combination, feed means for gripping the material on one side of the line, means for advancing the feed means to feed the material, a retainer for gripping the material constructed and arranged to engage the material rearward of the feed means at the end of the feeding movement, a folder, and means for actuating the folder to engage a portion of the material on the other side of the line and to fold the material into engagement with the retainer and past the retainer into contact with a portion of the material on the said one side of the line to cause the engaged portion of the material to be dragged frictionally past the retainer, the material being adapted to be pivoted about the feed member as a pivot.
21. A folding machine having, in combination, a retainer for holding a sheet of material, a folder for folding the material, and means for actuating the folder past the retainer, the folder being constructed and arranged to yieldingly engage the retainer during its actuation past the retainer to cause the folder to drag the material past the retainer.
22. A folding machine having, in combination, a movable support, a folder pivoted upon the support about two pivots disposed at an angle to each other, and means for moving the support to cause the folder to engage material on one side of a line of fold and to fold the engaged material about the line of fold toward the material on the other side of the line of fold.
23. A folding machine having, in combination, a movable support, a plow pivoted upon the support about a pivot, the plow being adapted to fold material, means for moving the support, and means for engaging the plow during the movement of the support to cause the plow to pivot about its pivot into engagement with the material to fold the material, the engaging means being normally out of engagement with the plow.
24. A folding machine having, in combination, a movable support, a plow yieldingly pivoted upon the support about a pivot, the plow being adapted to fold material, means for moving the support, and a yielding member for engaging the plow during the movement of the support to cause the plow to pivot yieldingly about the pivot into engagement with the material to fold the material, the yielding member being normally out of engagement with the plow.
25. A folding machine having, in combination, a movable support, a folder pivoted upon the support about two pivots disposed at an angle to each other, means for moving the support, means for yieldingly engaging the folder during the movement of the support to cause the folder to pivot about one of

the pivots to cause the folder to fold material, and means for causing the folder to pivot yieldingly about the other pivot to cause a further folding of the material.

26. A folding machine having, in combination, means for feeding material, a folder for folding the material, a fold presser for pressing the folded material and means for actuating the folder along substantially a straight-line path at an angle to the line of feed towards the fold presser.

27. A folding machine having, in combination, means for feeding material, a folder for folding the material, means for actuating the folder along substantially a straight-line path at an angle to the line of feed, and a fold presser for pressing the folded material situated at the end of the path of actuation of the folder.

28. A folding machine having, in combination, a folder for folding material, a fold presser for pressing the folder material, means for actuating the fold presser, and means connected to the actuating means for actuating the folder obliquely towards the fold presser along substantially a straight-line path.

29. A folding machine having, in combination, a folder for folding material, a fold presser for pressing the folded material, power-actuated means for actuating the fold presser, means connecting the power-actuated means with the fold presser, and means connecting the connecting means to the folder for actuating the folder.

30. A folding machine having, in combination, means for feeding material, a gear having an axis parallel to the line of feed, a support having a rack meshing with the gear obliquely disposed to the line of feed, a folder for folding the material, a fold presser for pressing the folded material, means for actuating the fold presser, and means connected to the actuating means for rocking the gear to effect the actuation of the folder.

31. A folding machine having, in combination, means for feeding material step by step, a retainer for holding the material against movement during pauses in the feed, a folder movable at an angle to the line of feed past the retainer to initiate folds in successive portions of the material, and a fold presser for pressing the folds.

32. A folding machine having, in combination, a folder, means for actuating the folder to fold material, a knife for cutting the material, and means controlled by the folder for actuating the knife.

33. A folding machine having, in combination, a folder, means for actuating the folder in two directions, the folder being constructed and arranged to fold material when actuated in one of the two directions, a knife for cutting the material, and means for actuating the cutter controlled by the folder

during its actuation in the other of the two directions.

34. A folding machine having, in combination, a folder, means for actuating the folder to an effective position to fold material and to an ineffective position, a knife for cutting the material, and means under the control of the operator controlled by the folder during its actuation to the ineffective position for actuating the knife.

35. A folding machine having, in combination, a movable support, a folder for folding material movably mounted upon the support, a knife for cutting the material, means for maintaining the knife normally in ineffective position, means for moving the support, means for engaging the folder during the movement of the support to cause the folder to move upon the support to fold the material, and means under the control of the operator constructed and arranged to be engaged by the support during the return movement of the support to effect the actuation of the knife.

36. A folding machine having, in combination, a folder for initiating a fold in a sheet of material, a fold presser for pressing the fold initiated by the folder, the fold presser having a portion adapted to press concave margins of the material, a portion adapted to press convex margins of the material, and a portion separating the said two portions, and means for actuating the folder towards the separating portion of the fold presser.

37. A folding machine having, in combination, a folder for initiating a fold in a sheet of material, a fold presser for pressing the fold initiated by the folder, means for feeding the material from the folder to the fold presser, the fold presser having a portion adapted to press concave margins of the material, a portion adapted to press convex margins of the material, and a portion separating the said two portions, the said two first-named portions being situated rearward of the separating portion in the line of feed, and means for actuating the folder obliquely to the line of feed towards the separating portion of the fold presser.

38. A folding machine having, in combination, a movable support, a folder pivoted upon the support about two pivots disposed at an angle to each other, a fold presser for pressing the fold initiated by the folder, means for feeding material from the folder to the fold presser, the fold presser having a portion adapted to press concave margins of the material, a portion adapted to press convex margins of the material, and a portion separating the said two portions, the said two first-named portions being situated rearward of the separating portion in the line of feed, means for moving the support obliquely to the line of feed towards the separating portion of the fold presser, means for yieldingly

engaging the folder during the movement of the support to cause the folder to pivot about one of the pivots to cause the folder to fold material, and means for causing the folder to pivot yieldingly about the other pivot towards the separating portion of the fold presser to cause a further folding of the material.

39. A machine for folding sheet material about a line of fold having, in combination, a folder for folding the material on one side of the line into contact with the material on the other side of the line, and means for controlling the folder to fold the portions of the material on the said one side of the line into contact with selectively predetermined portions of the material on the other side of the line.

40. A machine for folding sheet material about a line of fold having, in combination, a folder for folding the material on one side of the line step by step into contact with the material on the other side of the line, and means for causing the folder to exert a pull on the successive portions of the material during the folding action in a direction opposed to the pull exerted by the yet unfolded portions of the material.

41. A machine for folding sheet material about a line of fold having, in combination, means for feeding the material, a folder for folding the material, and means for actuating the folder to pull the material in the direction of feed at an angle to the line of fold during the folding action.

42. A folding machine having, in combination, a fold presser, a feed block and a feed point for feeding material to the fold presser step by step, a retainer for holding the material against movement during pauses in the feed, the retainer being spaced from the fold presser in the line of feed, and means for moving the feed block and the feed point back and forth between, but not beyond, the positions occupied by the retainer and the fold presser.

43. A folding machine having, in combination, a fold presser, a feed block and a feed point for feeding material to the fold presser step by step, a retainer for holding the material stationary during pauses in the feed, a folder, means for moving the folder diagonally to the direction of feed towards the fold presser, means for moving the feed block and the feed point back and forth between the retainer and the fold presser, whereby the paths of movement of the feed block and the feed point and of the folder converge towards the fold presser, and means whereby the retainer grips the stock after the feed block and the feed point release the material and before the fold presser grips the material.

44. A folding machine having, in combination, means for feeding material, a folder for initiating a fold in the material, means for

actuating the folder in a direction oblique to the line of feed along substantially a straight-line path, and a fold presser for pressing the fold initiated by the folder, the fold presser being situated immediately in front of the limiting forward position of the folder in the line of feed.

45. A folding machine having, in combination, a support, means for feeding material over the support, a retainer rearward of the feeding means in the line of feed for holding the material against the support, a folder for initiating a fold in the material, means for actuating the folder in a direction oblique to the line of feed along substantially a straight-line path to a position immediately forward of the retainer in the line of feed, and a fold presser for pressing the fold initiated by the folder, the fold presser being situated immediately in front of the limiting forward position of the folder in the line of feed.

46. A folding machine having, in combination, a support, means for feeding material over the support, a knife for slitting the margin of the material, a retainer oppositely disposed to the knife and rearward of the feeding means in the line of feed for holding the material against the support, a folder for initiating a fold in the margin of the material, means for actuating the folder in a direction oblique to the line of feed along substantially a straight-line path to a position immediately forward of the retainer in the line of feed, and a fold presser for pressing the fold initiated by the plow, the fold presser being situated immediately in front of the limiting position of the folder in the line of feed.

47. A folding machine having, in combination, a folder for folding a sheet of material step by step, a member, and means for relatively actuating the member and the folder intermittently past each other, the folder and the member being constructed and arranged to engage successive portions of the material frictionally between them during their relative actuation past each other to cause the said successive portions of the material to be dragged frictionally past the member.

48. A folding machine having, in combination, a support, means for actuating the support, a folder movably mounted upon the support, and means normally disengaged from the folder for engaging the folder at a predetermined point in the actuation of the support to actuate the folder to engage material on one side of a line of fold to fold the engaged material along the line of fold toward the material on the other side of the line of fold.

49. A folding machine having, in combination, a support, means for actuating the support, a folder yieldingly mounted upon the support, and a yielding member normally disengaged from the folder for engaging the

folder at a predetermined point in the actuation of the support to actuate the folder.

50. In a folding machine, in combination, folding instrumentalities comprising a member, a folder reciprocated in a right line across the member to fold the work thereabout, means for reciprocating said folder, and means for advancing the work past said instrumentalities.

10 51. In a folding machine, in combination, folding instrumentalities comprising a member, a folder reciprocated in a right line to fold the work about said member, means for reciprocating said folder, and means for advancing the work past said instrumentalities.

15 52. In a folding machine, in combination, a member, a folder having movements in a right line and provided with a margin-folding face, means for reciprocating said folder to cause its margin-folding face to fold the work-margin about said member, and means for feeding the work past said folder.

20 53. In a folding machine, in combination, a work-support, a folder reciprocable in a right line and having a margin-folding face, means for reciprocating said folder, a member across which said face is projected, and means for feeding the work past said folder.

25 54. In a folding machine, in combination, a work-support, work-feeding means, a folder movable in a right line, and means for reciprocating the said folder along the right line to engage material on one side of a line of fold to fold the engaged material about the line of fold toward the material on the other side of the line of fold.

30 55. A method of folding sheet material about a line of fold that comprises folding successive portions of the material on one side of the line part way about the line towards the material on the other side of the line in a direction substantially at right angles to the line, moving each partly folded portion so produced towards the next previously folded portion in a direction substantially parallel to the line, and folding each of the said partly folded and moved portions the rest of the way into contact with the material on the other side of the line.

35 56. A method of folding sheet material about a line of fold that comprises feeding the material, folding successive portions of the material on one side of the line part way about the line towards the material on the other side of the line, moving each partly folded portion in the direction of feed, and folding each of the said partly folded and moved portions the rest of the way into contact with the material on the other side of the line.

40 57. A method of folding sheet material about a line of fold that comprises folding successive portions of the material on one side of the line part way about the line towards the material on the other side of the line, and

moving each partly folded portion towards the next previously folded portion in a direction substantially parallel to the line.

58. A method of folding the margin of a shoe upper over upon the body portion thereof about a line of fold that constitutes a line of symmetry for corresponding successive portions of the material on opposite sides of the line, whereby each two corresponding symmetrically disposed portions are disposed on opposite sides of the line along a normal to the line, the said method comprising folding successive portions of the margin on one side of the line each into contact with the corresponding symmetrically disposed portion of the body portion on the other side of the line.

63 59. A method of folding the margin of a shoe upper over upon the body portion thereof about a line of fold that constitutes a line of symmetry for corresponding successive portions of the material on opposite sides of the line, whereby each two corresponding symmetrically disposed portions are disposed on opposite sides of the line along a normal to the line, the said method comprising folding successive portions of the margin on one side of the line each into contact with the corresponding symmetrically disposed portion of the body portion on the other side of the line and pressing the contacting portions together.

68 60. A method of folding the margin of a sheet of flexible non-metallic material over upon the body portion thereof that comprises folding successive portions of the margin and pulling upon each successive portion in a direction away from the adjacent unfolded margin.

73 61. A method of folding the margin of a sheet of flexible non-metallic material over upon the body portion thereof that comprises folding successive portions of the margin, pulling upon each successive portion in a direction away from the adjacent unfolded margin during the folding operation, and pressing the contacting portions together.

78 62. A machine for folding the margin of a sheet of flexible, non-metallic material over upon the body portion thereof about a line of fold that constitutes a line of symmetry for corresponding successive portions of the material on opposite sides of the line, whereby each two corresponding symmetrically disposed portions are disposed on opposite sides of the line along a normal to the line, the said machine having, in combination, means for folding successive portions of the margin on one side of the line each into contact with the portions of the body portion on the other side of the line, and means for insuring that each marginal portion shall be folded into contact with the corresponding symmetrically disposed portion of the body portion.

83 63. A machine for folding the margin of a

sheet of flexible, non-metallic material over upon the body portion thereof about a line of fold that constitutes a line of symmetry for corresponding successive portions of the material on opposite sides of the line, whereby each two corresponding symmetrically disposed portions are disposed on opposite sides of the line along a normal to the line, the said machine having, in combination, means for 10 folding successive portions of the margin on one side of the line each into contact with the corresponding symmetrically disposed portion of the body portion on the other side of the line, and means for pressing the contacting portions together.

64. A machine for folding the margin of a sheet of flexible non-metallic material over upon the body portion thereof having, in combination, means for folding successive 20 portions of the margin over upon the body portion thereof, and means for pulling upon each successive portion in a direction away from the adjacent unfolded margin.

65. A machine for folding the margin of a sheet of flexible non-metallic material over upon the body portion thereof having, in combination, means for folding successive portions of the margin over upon the body portion thereof and, during the folding operation, for pulling upon each successive portion in a direction away from the adjacent unfolded margin, and means for pressing the folded portions of the margin into contact with the body portion.

66. A folding machine having, in combination, a work-support, a folder movable in substantially a straight line in a direction substantially parallel to the work support, and means for reciprocating the folder along 40 substantially the said straight line to engage material on one side of a line of fold to fold the engaged material about the line of fold toward the material on the other side of the line of fold.

67. A method of folding the margin of a shoe upper over upon the body portion thereof about a line of fold, comprising relatively feeding the shoe upper, and folding successive marginal portions on one side of the line into contact with variably selected predetermined successive body portions on the other side of the line.

68. A machine for folding the margin of a shoe upper over upon the body portion thereof about a line of fold having, in combination, means for relatively feeding the shoe upper, and means for folding successive marginal portions on one side of the line into contact with selected predetermined successive body portions on the other side of the line.

In testimony whereof, I have hereunto subscribed my name this 7th day of April, 1924.

LEO J. LAMBERT.
